UNITED STATES PATENT OFFICE.

EUGENE F. DAVENPORT, OF MELROSE, MASSACHUSETTS, ASSIGNOR TO UNITED SHOE MACHINERY CORPORATION, OF PATERSON, NEW JERSEY, A CORPORATION OF NEW JERSEY.

SKIVING-KNIFE.

1,322,094.

Specification of Letters Patent.

Patented Nov. 18, 1919.

Application filed January 31, 1919. Serial No. 274,291.

To all whom it may concern:

Be it known that I, EUGENE F. DAVENPORT, a citizen of the United States, residing at Melrose, in the county of Middlesex and State of Massachusetts, have invented certain new and useful Improvements in Skiving-Knives; and I do hereby declare the following to be a full, clear, and exact description of the invention, such as will enable others skilled in the art to which it appertains to make and use the same.

The present invention relates to skiving knives and more particularly to skiving knives which embody a flexible knife blade held between a clamping member and a holder.

Skiving knives of the type disclosed in the pending application, Latham, Serial No. 216,735, filed February 12, 1918, are employed to a wide extent for beveling and splitting sheets of leather. As will be obvious to those skilled in the art, the knife blade is advanced in the holder when worn away until the greater portion of the blade has been used up, at which time the replacement of the worn blade by a new one is easily effected. It is of extreme importance in this class of knives that the cutting edge shall rotate in a true circle without the slightest deviation. In order to operate most efficiently on the work and with this end in view the clamping member is designed to cause all portions of the thin flexible knife blade to conform accurately to the true cylindrical holder so that in operation the knife blade is held rigidly and may not distort or buckle in use.

It is the object of the present invention to provide certain improvements in skiving knives of this type which shall in particular facilitate the clamping of the blade to the holder in such a manner that it may conform accurately throughout all portions to the shape of the holder and also permit the greatest possible portion of the knife blade to be utilized before the blade is discarded.

With this object in view, the novel features of the invention consist in certain features of construction, combinations and arrangements of parts hereinafter described and claimed, the advantages of which will be obvious to those skilled in the art from the following description.

In the accompanying drawings illustrating the invention, Figure 1 represents a lon-

gitudinal section partly in elevation of the skiving knife; and Fig. 2 represents a perspective view of the improved knife blade prior to its application to the holder.

It has been found with skiving knives of this type that the knife blade was limited to a depth or width which would permit its accurate conformation to the blade engaging surface of the holder. As the entire blade could not be utilized this resulted with the usual form of blade in rather frequent replacements. According to the present invention the knife blade is provided, upon its rear edge, with a series of attaching lugs or projections which serve to connect the blade with the carrier. These lugs are only large enough to afford the desired connection with the blade carrier and permit more or less freedom of distortion of the knife blade relative to the carrier; furthermore the use of the lugs permits substantially all of the knife blade to be effectively utilized, and in consequence materially increases the life of the blade prior to discarding.

The skiving knife shown in the illustrated embodiment of the invention is similar in its general construction to that disclosed in the Latham application above referred to. A blade holder 10 is threadedly mounted upon a shaft 11 and is provided with an accurately finished blade engaging surface 12. A flexible knife blade 14 is clamped against the surface 12 of the blade holder by a split clamping ring 15 which is secured to the hub 16 of a sleeve 17 journaled within the hollow knife shaft 11. The inner peripheral surface of the clamping ring 15 is tapered at 19 to engage with the correspondingly tapered face of an actuating member 20 rigidly connected to the end of a stem 21 sliding within the sleeve 17. The blade 14 is adjusted axially of the holder and clamping member by a carrier 23 which engages with the threaded barrel 24 of the clamping ring 15. Upon releasing the clamping ring 15 through the rod 21 the knife blade may be advanced through a rotation of the ring 15 by the hollow sleeve 17 in a manner well known to those skilled in the art.

As has been stated heretofore, it is of extreme importance in this class of constructions that the knife blade when clamped within the holder shall conform accurately to a true cylinder and in order to attain this end it is necessary to design the knife blade in such

a manner that it may freely conform to all portions of the blade engaging surface of the holder when the clamping ring is expanded. As shown in the drawings, more particularly Fig. 2, the knife blade comprises a thin band of tempered steel bent or formed into approximately the shape of a cylinder. One edge of the blade is beveled off in the usual manner to form the cutting edge and the opposite edge of the blade is cut away to form a series of spaced attaching lugs or projections 25 having their outer surfaces flush with the outer periphery of the blade and of sufficient width to properly connect the blade to the carrier without interfering with the clamping of the blade to the holder by the clamping ring. As will be observed from the drawings, each of the lugs 25 is provided with a teat 27 received in an annular groove 29 formed in the carrier 23. As will be observed from an inspection of Fig. 1, the body of the knife blade is out of contact with the carrier and the only connection between the blade and carrier is that afforded by the spaced lugs 25. With this construction substantially the entire knife blade may be utilized and as the lugs 25 are annealed to make them softer than the body portion of the blade a considerable distortion of the blade and lugs is permitted without tending to buckle or bend the knife blade as a whole.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A skiving knife comprising a blade

holder, a clamping member, a blade carrier adjustable axially of the holder and clamping member and a tubular knife blade adapted to be clamped between the holder and clamping member and having a series of separated integral lugs projecting from the rear edge to form the connection between the blade and carrier. 50

2. A skiving knife comprising a blade holder, a clamping member, a carrier adjustable axially of the holder, and a tempered steel knife blade of tubular form having lugs projecting from the rear edge of softer material to connect the blade to the carrier. 55

3. A skiving knife comprising an external holder, a clamping member, a blade carrier having an annular recess and adjustable axially of the holder, a knife blade having separated lugs projecting from the rear edge and provided with integral teats received in the recess to connect the blade to the carrier. 60 65

4. A skiving knife comprising a blade holder, a clamping member, a blade carrier adjustable axially of the holder and a tubular knife blade of substantial width having a cutting edge formed on one end and 70 having a series of separated lugs on the opposite end to connect the blade with the carrier.

5. A skiving knife comprising an external holder, a clamping member, a blade carrier 75 adjustable axially of the holder and having an annular recess formed therein and a tubular knife blade adapted to be clamped between the holder and clamping member having a series of separated lugs projecting 80 from the rear edge with their outer peripheral surfaces flush with the outer surface of the blade and each lug provided with an inwardly projecting teat received in the recess.

EUGENE F. DAVENPORT.
